(57) **CLAIM**

The ornamental design for an operation panel for elevator, as shown and described.

DESCRIPTION

FIG. 1. is a perspective view of the front, right, and top sides of an operation panel for elevator as viewed from a front showing my new design;

FIG. 2. is a front view thereof;

FIG. 3. is a rear view thereof;

FIG. 4. is a right side view thereof; a left side view being a mirror image thereof;

FIG. 5. is a top plan view thereof;

FIG. 6. is a bottom plan view thereof;

FIG. 7. is an enlarged front view thereof; taken along line 7-7 in FIG. 2;

FIG. 8. is an enlarged rear view thereof; taken along line 8-8 in FIG. 2;

FIG. 9. is an enlarged right side view thereof; taken along line 9-9 in FIG. 2;

FIG. 10. is an enlarged bottom plan view thereof;

FIG. 11. is an enlarged front view thereof; taken along line 11-11 in FIG. 2;

FIG. 12. is an enlarged rear view thereof; taken along line 12-12 in FIG. 2;

FIG. 13. is an enlarged right side view thereof; taken along line 13-13 in FIG. 2; and,

FIG. 14. is an enlarged top plan view thereof.
